CONCRETE MIXER

Anthony G. Zicovich, San Jose, Calif., assignor
of one-half to Arthur W. Caldwell, San Jose,
Calif.

Application August 30, 1947, Serial No. 771,414

18 Claims. (Cl. 259—178)

1

This invention relates to concrete mixers and is concerned more particularly with such apparatus embodying a non-rotatable mixing tank and means for providing an elevated point of discharge for the concrete.

In the trucking of concrete mixes from a central mixing plant to the construction job the usefulness of the pug mill concrete mixers embodying a non-rotatable mixing tank has been limited materially by the low level of the discharge means and by the difficulty of effecting discharge of the complete batch of concrete from the tank. The instant invention has for its general object the provision of improved concrete mixers of the above type which overcome the above-noted disadvantages and which provide for easy discharge of the complete batch of concrete at a desirable high elevation with reference to the mixer truck as well as to facilitate loading of either wet or dry mixtures into the mixing tank and mixing or agitation of the concrete mix while en route from the batch plant to the construction job.

The above and other objects of the invention will be apparent from the following description of certain preferred embodiments, as illustrated in the accompanying drawings, in which:

Figure 1 is a side elevational view, partly in section, of a concrete mixing truck having a pug mill mixer thereon embodying the instant invention, the mixer being shown in section.

Figure 2 is a rear elevation of the mixer.

Figure 3 is a front elevation of the mixer.

Figure 4 is a transverse sectional view of the mixer taken as indicated by the line 4—4 in Figure 1, the mixing blade being shown in a different operative position.

Figure 5 is a fragmentary plan view of the rear end of the mixer.

Referring to Figures 1 to 4, the mixing truck of the present invention includes a truck chassis 10 having a cab 11 and provided with the usual supporting wheels, only the rear wheels being shown. A stationary mixing tank 12 of the conventional pug mill type is supported on the truck chassis, and the mixing tank 12 is open at the top in a conventional manner with the top opening being defined by upright flange portions 12a.

Within the tank 12 there is a mixing assembly including a central shaft 13 upon which a spirally arranged mixing and progressing blade 14 is mounted by suitable radial arms 16. Suitable diagonally disposed bracing rods are also provided for the blade 14. The outer edge of the spiral blade 14 is formed as a resilient extension 14a of rubber material which effects a clean sweep

2

around the wall of the tank while yielding to permit passage of rocks in the mixture. The resilient blade portion 14a is bolted between a metal support strip 14b which is carried by the support arms 16 and a metal clamping strip 14c. The radial dimension of the unsupported edge of the resilient portion 14a of the mixing blade is comparable to the largest diameter of rock in the aggregate employed for the concrete mixture.

10 The drive for the shaft 13 (Figures 1 and 4) may be a suitable form of housed chain and sprocket drive connection including a connection 17 from the shaft 13 to an idler shaft 18, a drive connection 19 from the idler shaft 18 to a second idler shaft 20, and a drive connection 21 from the idler shaft 20 to a drive shaft 22. The drive shaft 22 is driven through a suitable clutch mechanism 23 from a power take-off shaft 24 extending to the conventional truck transmission 20 which has the usual gear shift lever associated therewith. A clutch control linkage 25 extends from the clutch 23 to the cab 11.

An elevated discharge of the concrete mix is provided at the rear of the mixer, and preferably closely adjacent a side thereof to provide for flexibility in the point of discharge of the mix either rearwardly or to the side of the mixer. The rear wall 26 of the mixer is provided with a rearwardly offset portion 26a providing an arcuate discharge passage disposed out of the path of the blade. In its lower portion the discharge passage has a discharge opening leading to a discharge ramp 27. A gate 28 is pivoted on the wall portion 26a at 29 and has pivoted thereto the plunger of a conventional pneumatic cylinder 31. The cylinder 31 is pivotally supported at 32 in spaced brackets 33 and is operable to move the gate 28 from the inclined closed position shown in Figure 1 to an open position.

40 Associated with the discharge ramp 27 (Figures 1, 2 and 5) is a discharge chute 36 pivoted at 37 on a horizontal axis in a bracket 38 which is pivotally supported at 39 about a vertical axis on a support bracket 40. The lower end 45 of the chute 36 is supported by a chain 41 whose upper end has a vertical pivotal mounting at 42 in vertical alignment with the pivoted support 39 of the discharge chute.

The blade structure of the invention has in addition to the spiral mixing blade 14, a plurality of lifting or discharge blades 46, and as shown, two opposite lifting blades 46 are provided which are helically shaped to correspond to the mixing blade 14. The blades 46 are also mounted on 50 the shaft 13 by suitable radial arms 15, and each

blade 46 includes a metal body portion 46a having bolted thereto a resilient radial or side edge portion 46b, and a resilient end portion or strip 46c. One of the lifting blades 46 is mounted with the mixing blade 14a, so that the resilient edge portion 14a thereof serves also as the edge 46b of the lifting blade. Referring to Figure 4, it will be noted that the wide end of a blade 46 is of a width corresponding to the width of the recessed or offset discharge passage 26a. As seen in Figure 5, the wide end of the tapered lifting blade structure, as well as the end of the spiral blade 14, depart from the general curvature of their helical shape and are disposed substantially at right angles to the adjacent end wall of the tank.

Referring to Figure 5, it will be noted that the immediate end portion of the spiral mixing blade 14 has a small straight section adjacent the end wall 26, and this small straight portion is occupied by the end strip 46c of the lifting blades. This edge portion operates closely against the end wall so that any material picked up by a lifting blade will be elevated along the end wall until it arrives at the recessed end wall portion 26a. The discharge chamber provided by the wall portion 26a allows for discharge of the material elevated by the lifting blade over approximately 90° of its travel when it will flow down onto the discharge ramp 27 if the gate 28 is open. When the gate 28 is in its inclined closed position, as shown in Figure 1, it covers the inner portion of the discharge ramp 27 and diverts the material back into the tank.

As previously explained, the drive for the mixing and progressing blade 14 and for the lifting blades 46 provides for counterclockwise rotation thereof, as viewed in Figure 4, so that the material is progressed by the blade toward the rearward end of the tank into cooperation with the lifting blades for elevation thereby to the discharge opening. The side edges of each lifting blade engage both the adjacent end and side walls to lift the material up the corner formed therebetween. It will be noted that the mounting of the lifting blade structure and its shaping to conform to the spiral of the mixing and progressing blade places the blade in an inclined position relative to the end wall 26 and the adjacent side wall. In this way concrete is pocketed between a lifting blade and the tank walls for elevation to the discharge opening. The resilient edge 14a of the progressing blade provides for a clean sweep around the wall of the tank so that substantially all of the material will be progressed to the discharge zone through which the blades 46 travel. At the same time the resilient edge 14a will yield if a stone does become lodged between it and the wall of the tank so that no jamming will occur. The front wall of the tank is engaged by a radial blade 43 which extends between the shaft and the blade 14, and which is constructed similarly to the blade 14 to provide a resilient edge portion. It will be noted that the wiping action of the resilient blades 14, 43 and 46 clean the respective walls of the tank during each rotation thereof.

While I have shown and described certain preferred embodiments of the invention, it is apparent that the invention is capable of variation and modification from the forms shown so that its scope should be limited only by the scope of the claims appended hereto.

I claim:

1. In a concrete mixer, a frame, a stationary

mixing tank on said frame having a discharge opening at an elevated position in an end wall thereof, means providing a recessed discharge passage offset with respect to said wall and extending upwardly from the bottom of said discharge opening, means disposed within the tank for progressing concrete therein toward said end wall, and a concrete elevating blade travelling through said tank adjacent said end wall and a contiguous side wall portion for picking up and carrying concrete to the recessed and offset discharge passage, said blade including detachable rubber edge portions for operation closely against the tank walls to thereby elevate substantially all of the pick-up concrete ingredients to said discharge opening without effecting appreciable separation of said ingredients.

2. In a concrete mixer, a frame, a stationary mixing tank on said frame having a discharge opening at an elevated position in a wall thereof adjacent the rear of the frame, a recessed discharge passage formed in said wall and extending upwardly from said discharge opening, means disposed within the tank for progressing concrete therein toward said wall, and concrete elevating means travelling through said tank adjacent said wall for picking up and carrying concrete to the discharge opening, said elevating means extending in the direction of progressing concrete through said tank and being mounted to operate closely against the interior of the tank to thereby elevate substantially all of the picked-up concrete ingredients to said discharge opening without effecting appreciable separation of the ingredients.

3. In a concrete mixer, a frame, a stationary mixing tank on said frame having a discharge opening at an elevated position in an end portion thereof, a recessed discharge passage at said end portion of said tank offset outwardly from said portion and extending upwardly from the bottom of said discharge opening, means disposed within the tank for progressing concrete therein toward said end portion and a concrete elevating blade travelling through said tank adjacent said end portion for picking up and carrying concrete to the discharge opening.

4. In a concrete mixer, a frame, a stationary mixing tank on said frame having a discharge opening at an elevated position in an end wall thereof, a recessed discharge passage formed in said end wall and extending upwardly from said discharge opening, means disposed within the tank for progressing concrete therein toward said end wall, and a concrete elevating blade travelling through said tank adjacent said end wall and a contiguous side wall portion for picking up and carrying concrete to the discharge opening, said blade having rubber edge portions for operation closely against the tank walls to thereby elevate substantially all of the picked-up concrete ingredients to said discharge opening without effecting appreciable separation of said ingredients.

5. In a concrete mixer truck of the type for use in transporting and mixing batches of concrete, a stationary mixing tank of generally cylindrical contour having a flanged open top, a spiral mixing and progressing blade mounted coaxially within the tank and disposed to move material toward an end wall thereof having a discharge opening at an elevated position thereon, a discharge ramp extending outwardly from said discharge opening, an offset portion of said wall extending upwardly from said opening to

provide a discharge passage overlying a portion of said ramp, an elevating blade mounted for rotation with said spiral blade and disposed to carry material upwardly to said discharge passage, and a gate for said opening having a closed position in which it is positioned to deflect material from said discharge passage back into said tank.

6. In a concrete mixer truck of the type for use in transporting and mixing batches of concrete, a stationary mixing tank of generally cylindrical contour having a flanged open top, a spiral mixing and progressing blade mounted coaxially within the tank and disposed to move material toward an end wall thereof having a discharge opening at an elevated position thereon, a discharge ramp extending outwardly from said discharge opening, an offset portion of said wall extending upwardly from said opening to provide a discharge passage overlying a portion of said ramp, an elevating blade mounted for rotation with said spiral blade and disposed to carry material upwardly to said discharge passage, a gate for said opening pivoted at its upper end to said offset wall portion and having a closed position in which it is positioned to deflect material from said discharge passage back into said tank, and a fluid-actuated cylinder mechanism for operating said gate.

7. In a concrete mixer truck of the type for use in transporting and mixing batches of concrete, a stationary mixing tank of generally cylindrical contour having a flanged open top, a spiral mixing and progressing blade mounted coaxially within the tank and disposed to move material toward an end wall thereof having a discharge opening at an elevated position therein, a discharged ramp extending outwardly from said discharge opening, an offset portion of said wall extending upwardly from said opening to provide a discharge passage overlying a portion of said ramp, an elevating blade mounted for rotation with said spiral blade and disposed to travel closely adjacent both the end and side walls of the tank and carry material upwardly to said discharge passage, and a gate for said opening having a closed position in which it is positioned to deflect material from said discharge passage back into said tank.

8. In a concrete mixer, a stationary mixing tank having an elevated discharge opening and a concrete elevating zone adjacent thereto, said zone being defined at least in part by a recessed wall portion of said tank extending above said discharge opening, a concrete progressor for progressing the concrete mix into said elevating zone, and elevating means travelling through said zone for picking up and carrying concrete mix to the discharge opening.

9. In a concrete mixer, a stationary mixing tank having an elevated discharge opening and a concrete elevating zone adjacent thereto, said zone being defined at least in part by a recessed wall portion of said tank, a concrete progressor for progressing the concrete mix into said elevating zone, and an elevating blade travelling through said zone for picking up and carrying concrete mix to the discharge opening and having a flexible edge portion for operation closely against the tank wall to thereby elevate substantially all of the picked-up concrete ingredients to said discharge opening without effecting appreciable separation of said ingredients.

10. In a concrete mixer, a frame, a stationary mixing tank having an elevated discharge opening and a concrete elevating zone adjacent there-

to, said zone being defined at least in part by a recessed discharge passage adjacent said elevating zone and being offset outwardly therefrom and extending upwardly from the bottom of said discharge opening, a concrete progressor for progressing the concrete mix into said elevating zone, and an elevating blade travelling through said zone for picking up and carrying concrete mix to the discharge passage and opening.

11. In a concrete mixer, a stationary mixing tank having an elevated discharge opening at one end thereof and including a recessed wall portion positioned above the discharge opening and leading to the discharge opening, means for elevating material into said recessed wall portion, and a gate for the opening disposed in its closed position to form a continuation of said wall portion and to thereby re-direct material from said recessed wall portion back into the tank.

12. In a concrete mixer, a stationary mixing tank of generally cylindrical contour, spirally arranged mixing and progressing blade means mounted for rotation within the tank to move the mixture therein into a discharge zone, said blade means including a resilient edge portion for engaging the tank wall, a plurality of elevating devices travelling through the discharge zone for lifting the concrete to an elevated point of discharge, said elevating devices extending in the direction of movement of the mixture through said tank and being mounted to operate closely with respect to the tank interior to thereby lift the concrete mixture to said point of discharge substantially intact without effecting appreciable separation of the ingredients of said mixture, and gate means at said elevated point of discharge.

13. In a concrete mixer of the type for use in transporting and mixing batches of concrete, a frame, a stationary mixing tank on said frame having a discharge opening at an elevated position in a wall structure of said tank and adjacent the rear of the frame, means providing a recessed discharge passage offset with respect to said wall structure and extending upwardly from the bottom of said discharge openings, means disposed within the tank for progressing concrete towards said wall structure, and concrete elevating means travelling through said tank adjacent said wall structure and past said discharge opening for elevating concrete along said wall structure to said recessed and offset discharge passage.

14. In a concrete mixer of the type for use in transporting and mixing batches of concrete, a frame, a stationary mixing tank on said frame having a discharge opening at an elevated position in a wall structure of said tank adjacent a rear corner thereof, means providing a recessed discharge passage offset with respect to said wall structure and extending upwardly from the bottom of said discharge openings, means disposed within the frame for progressing concrete towards said wall structure, and a concrete elevating blade mounted in inclined relation to said wall structure and for operation close to the interior of said tank wall structure for elevating concrete mixture along said wall structure to said recessed and offset discharge passage without effecting undesirable separation of the ingredients of said mixture.

15. In a concrete mixer of the type for use in transporting and mixing batches of concrete, a frame, a stationary mixing tank on said frame having a discharge opening at an elevated position in a wall structure of said tank and adjacent the rear of the frame, means providing a recessed

discharge passage offset with respect to said wall structure and extending upwardly from the bottom of said discharge opening, means disposed within the tank for progressing concrete mixture towards said wall structure, and a concrete elevating blade mounted for movement within said tank along a path extending upwardly past said recessed and offset discharge passage, said blade bearing an inclined relation to said wall structure to form a mixture retaining pocket therewith for elevation of concrete mixture along said path to said discharge opening.

16. In a concrete mixer of the type for use in transporting and mixing batches of concrete, a frame, a stationary mixing tank on said frame having a discharge opening at an elevated position in a wall structure of said tank and adjacent the rear of the frame, a spiral blade structure rotatably mounted in said tank for progressing material towards said wall structure, an elevating blade carried by said blade structure adjacent one end thereof and generally shaped to conform to the spiral of said blade structure and forming with said wall structure a pocket capable of retaining concrete mixture during elevation thereof for discharging the mixture from the tank.

17. In a concrete mixer of the type for use in transporting and mixing batches of concrete, a stationary mixing tank having an elevated discharge opening adjacent one end thereof and including a recessed wall portion positioned above the discharge opening and leading to the discharge opening, means for elevating material in-

to said recessed wall portion, and a gate for the opening.

18. In a concrete mixer of the type for use in transporting and mixing batches of concrete, a stationary mixing tank of generally cylindrical contour, a spiral mixing and progressing blade mounted coaxially within the tank and disposed to move the material toward a wall structure thereof having a discharge opening at an elevated position thereon, a discharge ramp extending outwardly from said discharge opening, an offset portion of said wall structure extending upwardly from said opening to provide a discharge passage overlying a portion of said ramp, an elevating blade mounted for rotation with said spiral blade and disposed to carry material upwardly to said discharge passage, and a gate for said opening.

ANTHONY G. ZICOVICH.
